UNITED STATES PATENT OFFICE.

LILLIAN RUDERSDORF, OF CHICAGO, ILLINOIS.

STRAIGHTEDGE DEVICE.

Application filed March 25, 1920. Serial No. 368,652.

To all whom it may concern:

Be it known that I, LILLIAN RUDERSDORF, a citizen of the United States, residing at Chicago, in the county of Cook and State of Illinois, have invented a new and useful Improvement in Straightedge Devices, of which the following is a specification.

This invention relates particularly to a device in the nature of a straight edge adapted for photograph retouching, artists' poster work, etc.

The primary object of the invention is to provide an improved device well adapted to the purpose indicated.

15 The invention is illustrated in its preferred embodiment in the accompanying drawing, in which—

Figure 1 represents a plan view of the improved device; Fig. 2, an elevational view of 20 the same; Fig. 3, a sectional view taken as indicated at line 3—3 of Fig. 1; and Fig. 4, a perspective view of one of the adjustable bearing blocks employed.

In the construction illustrated, A represents a straight edge strip; and B, B', bearing blocks which are adjustable longitudinally with relation to the strip A.

In the illustration given, the straight edge strip A is provided with straight edges 1 30 and 2, the latter being undercut.

The member A is provided centrally with a longitudinal slot 3, which is reduced at its lower portion, as indicated at 3^a. The slot extends from near one end of the member A 35 to near the other end thereof. Each of the bearing blocks B and B' may, preferably, be of the form illustrated in Fig. 4. Thus, each block is provided on its upper side with a central elongated tenon, or spline, 4, which 40 works in the reduced portion 3^a of the slot as a guide. The blocks are adjustably secured by means of screws 5 equipped with washers 5^a. The washers 5^a bear upon the shoulder afforded by the bottom of the wide portion 45 of the slot, and the screws extend through the slot and into the blocks and serve to clamp the blocks to the strip A. The guide-tenons 4 are low enough so that they will project slightly less than flush with the bottom 50 of the wide portion of the slot. Thus, the blocks can be securely clamped to the strip A at any desired point.

In the use of the improved device for the purpose of retouching photographs, for ex-

ample, the blocks are adjusted to bear upon 55 the card, or mounting, of the photograph at opposite sides of the photograph proper; and the retouching can be done upon the photograph by means of a pen, the strip A being used as a straight edge. The improved 60 device is adapted to be adjusted to the work of retouching photographs of varying width. The blocks may be caused to bear upon the card in such manner as to cause it to lie flat 65 while the work of retouching is performed. This is of especial advantage in work of retouching photographs, which have a tendency to curl up or warp. The device may be employed, also, for artists' poster work 70 and similar work.

The form illustrated affords a cheap and satisfactory construction for most purposes. The strip A and the blocks B may be composed of wood. Any suitable adjustable connection between the blocks and the strip may 75 be employed. The blocks are short enough in a direction transversely of the strip A to enable the edge portion of the strip to project over the blocks. Ordinarily, the strip A will have straight edges, as shown. 80

What I regard as new, and desire to secure by Letters Patent, is:

1. A device of the character set forth, comprising a strip adapted for ruling purposes, and bearing blocks disposed wholly on 85 one side of said strip and adjustably connected therewith for adjustment longitudinally of the strip, said blocks being adapted to rest upon a card which is to be ruled.

2. A device of the character set forth, 90 comprising a strip provided with a straight edge adapted for ruling purposes, said strip being provided with a longitudinal slot, bearing blocks disposed on one side of said strip and slidably connected with said slot, 95 and means for clampingly securing said bearing blocks to said strip.

3. A device of the character set forth, comprising a strip provided with a straight edge adapted for ruling purposes, said strip 100 being provided with a longitudinal slot, bearing blocks disposed on one side of said strip and slidably connected with said slot, said blocks being wholly covered by said strip, and means for clampingly securing 105 said bearing blocks to said strip.

LILLIAN RUDERSDORF.
